UNITED STATES PATENT OFFICE.

VIOLETTA H. BIOREN, OF NEWARK, NEW JERSEY.

DESIGN FOR A TIP FOR CHAIR-ROCKERS.

SPECIFICATION forming part of Design No. 24,861, dated November 5, 1895.

Application filed October 2, 1895. Serial No. 564,458. Term of patent 7 years.

To all whom it may concern:

Be it known that I, VIOLETTA H. BIOREN, a citizen of the United States, residing at Newark, in the county of Essex and State of New Jersey, have invented a new and original Design for Chair-Rocker Tips, fully described and represented in the following specification and the accompanying drawings, forming a part of the same.

10 This invention relates to a special form for that class of shields commonly applied to the ends of chair-rockers for protecting contiguous articles of furniture from injury by contact therewith; and it consists in the specific 15 shape for such article shown in the annexed drawings, in which—

Figure 1 is a side view, Fig. 2 an end view, and Fig. 3 a perspective view, of the article.

15 The shield or tip is formed with a hollow 20 substantially wedge-shaped body *a* of rectangular cross-section, having one of its convergent faces curved toward the other, which is

substantially flat, both terminating in the rounded transverse bead or protuberance *b*, extending the entire width of the wedge and 25 concealing the line of intersection of the said convergent faces.

The essential feature of the design is the peculiar wedge form of the article, having its convergent faces terminating in the trans- 30 verse bead of rounded form.

Having thus set forth the invention, what I claim herein, and desire to secure by Letters Patent, is—

The design for a chair rocker tip herein 35 shown and described.

In testimony whereof I have hereunto set my hand in the presence of two subscribing witnesses.

VIOLETTA H. BIOREN.
